(57) **CLAIM**

The ornamental design for an eye part for hook and eye fastener, as shown and described.

DESCRIPTION

FIG. 1 is a perspective view of an eye part for hook and eye fastener showing our new design;

FIG. 2 is a front elevational view;

FIG. 3 is a rear elevational view;

FIG. 4 is a top plan view;

FIG. 5 is a bottom plan view;

FIG. 6 is a right side elevational view;

FIG. 7 is left side elevational view;

FIG. 8 is a perspective view of an eye part for hook and eye fastener showing a second embodiment of our new design;

FIG. 9 is a front elevational view of FIG. 8;

FIG. 10 is a rear elevational view of FIG. 8;

FIG. 11 is a top plan view of FIG. 8;

FIG. 12 is a bottom plan view of FIG. 8;

FIG. 13 is a right side elevational view of FIG. 8;

FIG. 14 is left side elevational view of FIG. 8;

FIG. 15 is a perspective view of an eye part for hook and eye fastener showing a third embodiment of our new design;

FIG. 16 is a front elevational view of FIG. 15;

FIG. 17 is a rear elevational view of FIG. 15;

FIG. 18 is a top plan view of FIG. 15;

FIG. 19 is a bottom plan view of FIG. 15;

FIG. 20 is a right side elevational view of FIG. 15;

FIG. 21 is left side elevational view of FIG. 15;

FIG. 22 is a perspective view of an eye part for hook and eye fastener showing a fourth embodiment of our new design;

FIG. 23 is a front elevational view of FIG. 22;

FIG. 24 is a rear elevational view of FIG. 22;

FIG. 25 is a top plan view of FIG. 22;

FIG. 26 is a bottom plan view of FIG. 22;

FIG. 27 is a right side elevational view of FIG. 22; and,

FIG. 28 is left side elevational view of FIG. 22.
